ABSTRACT

A circuit breaker characterized by spring means for closing contacts, means for charging the spring means and including a crank shaft structure, a ratchet wheel rotatably mounted on the shaft, driving pawl means operable to advance the ratchet wheel for charging the spring means, means moving the charging pawl means out of driving engagement with the ratchet wheel when the spring means are charged. Means is also provided to permit movement of the crank shaft structure relative to the ratchet wheel upon discharge of the closing spring.

CIRCUIT BREAKER INCLUDING SPRING CLOSING MEANS WITH MEANS FOR MOVING A CHARGING PAWL OUT OF ENGAGEMENT WITH A RATCHET WHEEL WHEN THE SPRING MEANS ARE CHARGED

CROSS-REFERENCE TO RELATED APPLICATION

This invention is related to inventions disclosed in the application of N. J. Patel, Ser. No. 770,236, filed Oct. 24, 1968 (now U.S. Pat. No. 3,544,931), of Fred Bould et al., Ser. No. 770,296, filed Oct. 24, 1968 (now U.S. Pat. No. 3,590,192), and of Fred Bould, Ser. No. 874,648, filed Nov. 6, 1961, (now U.S. Pat. No. 3,600,540) and application Ser. No. 181,012, filed Sept. 16, 1971.

BACKGROUND OF THE INVENTION

2. Field of the Invention

This invention relates to a motor operated spring-closing circuit breaker and, more particularly, it pertains to an improved circuit breaker having spring means for closing the contacts which spring means are constrained from operation by a ratchet wheel and pawl associated therewith.

2. Description of the Prior Art

Certain types of circuit breakers are provided with spring means for closing the circuit breaker contacts. In the past, the springs have been charged by a ratchet wheel fixedly mounted on a shaft for charging the springs. For example, in U.S. Pat. No. 3,254,186, a ratchet wheel is mounted on a crank shaft for charging springs for closing the circuit breaker contacts. Discharge of the springs is prevented only by the ratchet wheel and a holding pawl. One disadvantage of that type of structure has been chipping and breakage of the ratchet wheel teeth particularly during free discharge of springs.

Various attempts to overcome that disadvantage have been made including a ratchet wheel which is rotatably mounted on shaft and disengaged from the charging spring system during the discharge thereof. The ratchet wheel has been provided with a so-called "missing tooth" portion which had the effect of disengaging the charging pawl from the ratchet wheel when the spring means are completely charged. This in turn incurs a disadvantage in that the ratchet wheel turned by random amounts results in the holding pawl or charging pawl engaging the missing tooth portion instead of the toothed portion of the ratchet wheel upon subsequent charging of the spring means. Accordingly, the use of a ratchet wheel which is rotatably mounted on a charging shaft and having a missing tooth portion does not completely satisfy the disadvantages of chipping and breakage of ratchet wheel teeth. The U.S. Pat. No. 2,961,067 discloses a ratchet wheel with a missing tooth portion.

SUMMARY OF THE INVENTION

It has been found in accordance with this invention that the foregoing problems may be overcome by providing a ratchet wheel which is rotatably mounted on a crank shaft and having no "missing tooth" portion. In conjunction with clutch means including a charge plate fixedly mounted on the charge shaft and rotatable with the ratchet wheel when actuated by pin means ex-

tending from the ratchet wheel. The ratchet wheel is disengaged from the charged plates through a rotation of about 330°, thus preventing any movement of the ratchet wheel during discharging of the springs. Finally, the charge plates include camming edges for disengaging the charging pawl from the ratchet wheel when the spring means are in the charged position.

The advantage of the improved charging system for circuit breakers of this invention is not only the avoidance of the problem of breaking and chipping ratchet teeth but also the provision of a positive-acting clutch that disengages the reciprocating charging pawl when the springs are in the fully charged position and, thereby preventing damage to the teeth for any reason, such as failure of the charging motor to shut off when necessary. A further advantage is that the charge plates are free to rotate through approximately 330° (as compared with only 160° in present constructions), thereby providing positive disengagement of the ratchet wheel from the charge plates and shaft which rotate and oscillate about the spring dead center during the discharge of associated spring means.

BRIEF DESCRIPTION OF THE DRAWINGS

FIG. 1 is an end view with parts broken away and certain parts omitted for clarity of a circuit breaker constructed in accordance with this invention;

FIG. 2 is a sectional view taken generally along the line II-II of FIG. 1;

FIG. 3 is a partial sectional view taken generally along the line III-III of FIG. 1 with the crank shaft and the closing spring shown in the charged position;

FIG. 4 is a partial sectional view with parts broken away and showing the crank shaft and closing spring in the discharged position;

FIG. 5 is an enlarged fragmentary end view of the spring charging mechanism; and

FIG. 6 is an exploded isometric view of the spring charging mechanism with the spring in the charged position.

DESCRIPTION OF THE PREFERRED EMBODIMENT

Referring to the drawings, there is shown in FIGS. 1 and 2 a three-pole circuit breaker 5 comprising a support structure or housing 7 and a circuit breaker structure 9 supported on the housing structure. The housing structure 7 comprises a metallic base plate 11, a pair of spaced metallic side plates 13 fixedly secured to flanges of the base plate, a pair of metallic center plates 17 fixedly mounted on the base plate, and a back wall structure indicated generally at 19.

The circuit breaker structure 9 is a three-pole structure comprising a stationary contact 21 (FIG. 2) and a movable contact 23 for each pole unit. Each of the movable contacts 23 is supported on a conducting contact arm 25 that is pivotally supported on a terminal conductor 27 by means of a pivotal support means 29. In each pole unit, a separate insulating connecting member 31 is pivotally connected at one end thereof to the contact arm 25 and at one end thereof to the contact arm 25 and at the center end thereof a lever 33 that is welded to a common jack shaft 35 that extends across all of the poles of the circuit breaker. There is a separate lever 33 for each pole unit welded to the com-

mon jack shaft 35. Only one of the contact structures is shown in FIG. 1. The contact structures for the center pole and for the left-hand pole (FIG. 1) are omitted from the drawing in FIG. 1 merely for clarity. It can be understood that the contact structures for all three pole units are the same as the one contact structure shown in FIGS. 1 and 2.

The jack shaft 35 is supported for pivotal movement, about the elongated axis thereof, on the side plates 13 and center plates 17. The connecting member 31, levers 33, and jack shaft 35 are part of a stored-energy spring-closing mechanism 39 that is operable to close the contacts 23, 21. The mechanism 39 comprises a link 41 that is pivotally connected, at one end thereof, to the lever 33 of the center pole by means of a pin 43. The link 41 is pivotally connected at the other end thereof, to a link 45 by means of a knee pivot pin 47. A roller member 49, that serves as a cam follower, is mounted on the pin 47 to cooperate with a closing cam 51. The link 45 is pivotally connected at the other end thereof to a latch member 53 by means of a pin 55. The latch member 53 is mounted for pivotal movement about a fixed pivot pin 57 that is supported on the left-hand (FIG. 1) center plate 17. A tension spring 59 is connected to the pin 55 to reset the linkage following a tripping operation of the circuit breaker. The latch member 53 engages the periphery of a trip shaft 63 in proximity to a cut-out portion of the shaft 63, which cut-out portion is provided so that when the trip shaft 63 is rotated in a counterclockwise direction the latch member 53 will be free to move into the cut-out portion to the tripped position. The trip shaft 63 is supported for pivotal movement about the elongated axis thereof between one of the center plates 17 and one of the side plates 13.

A roller latch 67 (FIG. 2) is rotatably supported on and between the twin plates of the closing shaft 71 that is rotatably supported on suitable bearings that are secured to the center plates 17. A pair of crank arms 73 are fixedly mounted on the crank shaft 71 at the opposite ends of the crank shaft.

As shown in FIGS. 3 to 6 a ratchet member or wheel 74 is rotatably mounted on the crank shaft 71, as evidenced by a circular hole 74a. A pair of charge plates 75 and 76 are fixedly mounted on the crank shaft 71 and on opposite sides of the ratchet wheel 74. The plates 75 and 76 include the strike surfaces 75a and 76a, respectively, as well as the camming surfaces 75b and 76b, respectively. A projection or pin 77 having opposite end portions extending from opposite sides of ratchet wheel 74 are disposed in the paths of travel of the strike surfaces 75a and 76a. The crank shaft 71, crank arms 73, and plates 75, 76, move in unison as a crank shaft structure 77a. A reciprocable member 78 is rotatably mounted on crank shaft 71 where it is supported for pivotal reciprocating movement relative to the crank shaft to cooperate with the ratchet wheel 74 and charge plates 75 and 76.

As the member 78 turns the ratchet wheel 74 counterclockwise (FIG. 4) the pin 77 (bearing against the strike surfaces 75a and 76a) rotate the charge plates 75 and 76 and hence the crank shaft 71 is turned from the discharged position (FIG. 4) to the charged position (FIG. 3). When the charged position is reached, the camming surface 76b lifts the lever 111 (FIG. 6) and

the charge pawl 107 is disengaged from the ratchet 74. Once the charge plates reach the charge position as shown by the broken line position 76a (FIG. 3), the tension in the springs 79 is sufficient to rotate the pin 80 below a line through the axes of the shaft 71 and the rod 82 to the solid line position of the plates. This action is arrested when the latch roller 67 strikes the member 85 (FIG. 2).

A separate tension spring 79 is operatively connected at the end of each of the crank arms 73 by means of a pivot pin 80. Each of the springs 79 is connected to a spring support 81 that is pivotally connected to the associated arm 73 by means of the associated pivot pin 80. Each of the tension springs 79 is connected, at the other end thereof, to a rod 82 that is secured to the center plate 17. A manual operating mechanism, indicated generally at 83 (FIG. 1), is provided for manually charging the closing springs 79. A latch member 85 (FIG. 2) is pivotally mounted on a pin 87 and biased in a clockwise (FIG. 2) direction to the latching position wherein the latch 85 engages the roller 67 to latch the closing cam 51 and crank shaft 71 to prevent counterclockwise movement of the closing cam 51 and crank shaft 71.

The circuit breaker is shown in FIG. 2 in the contact open position with the stored energy closing springs 79 in the charged condition. As is shown in FIG. 2, the spring support pins 80 of the tension springs 79 are below a line between the center of the spring support rod 82 and the center or axis of the crank of shaft 71 so that the charged tension springs 79 are operating to bias the crank shaft 71 in a counterclockwise direction. Counterclockwise movement of the crank shaft 71 is prevented by the engagement of the latch member 85 with the latch roller 67 that is mounted on the closing cam 51. The latch member 85 is operated to the unlatching position to close the circuit breaker in a manner described in the above-mentioned Pat. No. 3,590,192.

When it is desired to close the breaker, the latch 85 is pivoted in a counterclockwise (FIG. 2) direction to thereby release the roller 67. When the roller 67 is released, the closing cam 51 and the crank shaft 71 are free to rotate in a counterclockwise direction, and the closing springs 79, operating on the crank arms 73, operate to rotate the crank shaft 71 in a counterclockwise direction as the spring 79 discharge. During this movement, the closing cam 51 will force the roller 49, and the link 41 upwardly to the closed position. During this closing movement of the link 41, of the lever 33 (FIG. 2) of the center pole unit is forced in a counterclockwise direction to rotate the jack shaft 35 counterclockwise to simultaneously move the three contact arms 25 in a clockwise direction about the pivots 29 to the closed position. In the closed position, the engagement of the closing cam 51 with the roller 49 serves to prop the link member 41 in the closed position to thereby maintain the jack shaft 35 and contacts 23 in the closed position.

With the contacts in the closed position and the closing spring 79 discharged, the circuit breaker may be automatically tripped open, in response to an overload above a predetermined value in any of the pole units, by operation of the trip shaft 63 in a manner described in the U. S. Pat. No. 3,544,931. During the tripping

operation, the trip shaft 63 is rotated in a counter-clockwise (FIG. 2) direction. When the trip shaft 63 is rotated counterclockwise, the trip shaft moves to permit the latch member 53 to move into the cut-out portion of the trip shaft 63, thereby permitting the latch member 53 to move in a counterclockwise direction about the pivot 57 to the tripped position. The compressed contact springs 93 (FIG. 2) and an opening spring 99 (FIG. 1) then operate to move the contact arms 25 toward the open position which movement occurs because the pivot 55 is free to move so that the link 45 can move to the tripped position with the toggle 45, 41 collapsing to permit the lever 33 and jack shaft 35 to move in a clockwise direction to the tripped open position. Thus, movement of the trip shaft 63 to the tripped position permits the members 41, 45, 53 to move to the tripped position, wherein the roller 49 and link 41 no longer restrain the lever 33 in the closed position, and the springs 93, 99 operate to move the jack shaft 35 and the three contact arms 25 to the tripped open positions.

With the circuit breaker in the tripped open position, the breaker is reset and the closing springs 79 are charged by operation of the motor-drive structure 101 in a manner to be hereinafter more specifically described. In order to reset the circuit breaker and charge the closing springs 79, the crank arm 73 is rotated from the spring discharged position of FIG. 4 through an angle of more than 180° to the spring charged position of FIGS. 2 and 3. As the crank shaft 71 moves to the position seen in FIG. 2, the roller 49 rides off of the peak of the cam 51 into the depression seen in FIG. 2. When the roller 49 is free to move into the depression of the cam 51, the spring 59 (FIG. 1) biases the latch 53 clockwise (FIG. 2) to move the latch 53 to the reset position pulling links 45, 41 and the roller 49 to the reset position wherein the roller 49 is positioned in the depression of the cam 51 (FIG. 2). When the latch 53 moves out of the notch of the trip shaft 63, suitable spring means operates to rotate the trip shaft 63 clockwise to the latching position wherein the periphery of the trip shaft 63 again latches the latch member 53 to latch the parts in the reset position seen in FIG. 2. As the crank shaft 71 moves more than 180° to the position seen in FIGS. 2 and 5 the springs 79, which are moved over-center, take over to bias the crank shaft 71 in a counterclockwise (FIG. 2) direction, and the roller 67 engages the latch 85 to latch the crank shaft 71 in the charged position seen in FIG. 2, and the circuit breaker is prepared for another closing operation.

When the circuit breaker is in the contact-closed position with the stored energy closing springs 97 discharged the spring closed means is operated to the charged position by operation of the motor drive structure 101 (FIG. 5) to rotate the crank shaft 71 through an angle of slightly more than 180° (approximately 184°) to charge the springs 79 during which movement the roller 49 rides on a fixed radius of the cam 51 to a position just short of the peak of the cam surface of the cam member 51. This charging movement of the cam 51 is more specifically described in the above-mentioned U.S. Pat. No. 3,590,192.

With the parts in the contact closed spring charged position, the following sequence of operations can occur.

Upon the occurrence of an overload above a predetermined value, the trip means indicated generally at 95 (FIG. 1) is automatically operated to rotate the trip shaft 63 to release the latch member 53 and permit the toggle 41, 45 to effect an opening operation in the same manner as was hereinbefore described. With the toggle 41, 45 collapsed, the spring 59 operates to draw the roller 49 into the depression of the cam 51 resetting the linkages 53, 41, 45 and the trip shaft 63 is moved by spring means into the latching reset position seen in FIG. 2. The parts at the end of this tripping operation are in the position seen in FIG. 2, wherein the mechanism is reset and relatched, and wherein the roller member 49 is in the depression of the cam 51 so that the parts are prepared for a closing operation. When the closing springs 79 are charged, an operator can immediately operate the closing latch 85 (FIG. 2) to release the roller 67 whereupon the circuit breaker is operated to the closed position in the same manner as was hereinbefore described. With the parts in the closed position, if an overload above the predetermined value occurs the trip means 95 will be automatically operated to rotate the trip shaft 63 to the tripped position to effect a tripping operation in the same manner as mentioned before described. With the parts in the tripped position and the closing springs 79 discharged, another charging operation of the closing springs 79 will be required in order to provide another closing operation. Thus, when the circuit breaker is in the contact closed spring charged position, the circuit breaker can be tripped and then closed and then tripped again in rapid sequence.

The reciprocating member 78 (FIGS. 3 to 6) comprises a circular opening 105 and a flange or bight portion 106. The reciprocating member 78 is rotatably mounted on the crank shaft 71 for movement relative to the crank shaft about the axis thereof. A charging pawl 107 also is pivotally mounted on the oscillating member 78 by means of a pin 108, and a torsion spring 109 biases the pawl 107 in a counterclockwise direction about the pin 108 into engagement with the ratchet wheel 74. The pawl 107 also includes a lever 111 as an integral part which lever has an end portion 112 that is contacted and lifted by the camming surface 75b when the charge plate 75 is in the charge position (FIGS. 3 and 6), whereby the pawl 107 is raised out of operation with the ratchet wheel teeth. A tension spring member 113 biases the reciprocating member 78 in a clockwise direction (FIG. 3) about the crank shaft 71. A holding pawl 114 is pivotally mounted on one of the center plates 17 by means of a pin 115 and biased in a counterclockwise direction, by means of a torsion spring 116, into engagement with the ratchet wheel 74.

The drive motor 101 comprises an output shaft 133 (FIG. 5). An arm 137 is mounted on the end of the shaft 133 and a roller member 139 is rotatably mounted on a pin 141 that is supported on the arm 137.

As can be seen in FIG. 3, the closing springs 79 are in the charged position with the closing latch 85 (FIG. 2) engaging the roller 67 of the cam 51 to latch the crank shaft 71 in the spring charged position shown in FIG. 3. Upon the release of the latch 85, the springs 79 discharge rotating the crank shaft 71 slightly more than 180° to close the circuit breaker in a manner hereinbefore described. Upon discharge of the closing springs

79 suitable limit switch means is actuated in a well known manner by the breaker mechanism to energize the drive motor 101. Upon energization of the drive motor 101, the arm 137 is rotated in a clockwise (FIG. 3) direction about the axis thereof at a suitable rate such as 500 rpm.

During each revolution of the output shaft 133 the roller 136, operating against the bight part 107 of the oscillating member 78 moves the oscillating member in a counterclockwise direction during which movement the driving pawl of 109 operates against one of the teeth of the ratchet 74 to advance the ratchet and crank shaft 71. As the roller arm 137 moves 180° from the position seen in FIG. 4, the member 78 will advance the ratchet 74 and crank shaft 71 in a counterclockwise direction, and as the roller arm 137 moves the remaining 180° of a 360° revolution, the spring 113 will return the member 78 to the position seen in FIG. 3 with the holding pawl 121 holding the ratchet 74 and crank shaft 71 in the advanced position. Thus, as the output shaft 133 rotates, the ratchet 74 is advanced by the charging pawl 107 and alternately held by the holding pawl 114 until the crank shaft 71 moves more than 180° to an over-center position wherein the charged closing springs 79 again bias the crank shaft 71 in a counterclockwise direction with the ratchet 74 and crank shaft 71 becoming latched from closing movement by the latch member 85 (FIG. 2) which engages the roller 67 on the cam 51 that is fixed to the crank shaft 71. When the closing springs 79 reach the fully charged position, the charging pawl 107 is disengaged from the teeth (FIG. 3) of the ratchet 74 so that continued rotation of the motor will not operate against the teeth of the ratchet 74, and the motor can be brought to a stopped condition without damaging the parts and without putting undue forces on the parts. The motor 101 is automatically deenergized by suitable limit switch means in a manner well known in the art.

Upon release of the springs 79, the charge plates 75 and 76 stop ultimately at the position shown in FIG. 4 whereas the pin 77 remains in the same position. When the springs reach the discharged position (FIG. 4), the pivot pin 80 overshoots the dead center position due to the high velocity developed and then oscillates clockwise and counterclockwise with reducing amplitudes until the energy is completely dissipated. However, the ratchet 74 remains stationary and undisturbed by the discharge operation as noted by the similar position of the pin 77 in FIGS. 3 and 4.

What is claimed is:

1. A circuit breaker comprising a pair of contacts operable between open and closed positions, a crank shaft structure, closing spring means connected to said crank shaft structure, a ratchet wheel movable to move said crank shaft structure from a spring discharged position to a spring charged position to charge said closing spring means, releasable latch means latching

said crank shaft structure in said spring charged position, a reciprocating drive pawl structure in driving engagement with said ratchet wheel, operating means operable to reciprocate and drive pawl structure to move said ratchet wheel to thereby move said crank shaft structure from said spring discharged position to said spring charged position, and disengaging means operating automatically when said crank shaft structure is moved to said spring charged position to move said drive pawl structure out of driving engagement with said ratchet wheel.

5 2. A circuit breaker comprising a pair of contacts movable relative to each other between opened and closed positions, closing spring means operable to a charged condition for moving the contacts to the closed position, means for charging the spring means and including a crank shaft and a ratchet rotatable with respect to the crank shaft, rotatable means fixedly mounted on the crank shaft, projection means on and extending from the ratchet, a portion of the rotatable means being disposed in the path of travel of the projection means, the charging means also including a reciprocating charge pawl operable to advance the ratchet for charging the closing spring means, holding pawl means for constraining the ratchet, means on the rotatable means for disengaging the charge pawl when the closing spring means are in the charged condition, means for releasing the closing spring means from the charged condition and operatively connecting the spring means with at least one of the contacts for moving the contacts to the closed position.

10 3. The circuit breaker of claim 2 in which the ratchet is a wheel rotatable on the axis of the crank shaft.

15 4. The circuit breaker of claim 3 in which the ratchet wheel is rotatably mounted on the crank shaft.

20 5. The circuit breaker of claim 2 in which the projection means is a pin extending from one side of the ratchet wheel.

25 6. The circuit breaker of claim 5 in which the pin is disposed in an axis substantially parallel to that of the rotation of the ratchet.

30 7. The circuit breaker of claim 2 in which the rotatable means is a charge plate.

35 8. The circuit breaker of claim 7 in which the plate includes a strike surface in the path of travel of the projection means.

40 9. The circuit breaker of claim 2 in which the rotatable means is a plate and in which the disengaging means is a cam surface operable to lift the charge pawl out of engagement with the ratchet.

45 10. The circuit breaker of claim 2 in which the projection means extend from opposite sides of the ratchet, in which the rotatable means include a plate on opposite sides of the ratchet, in which the ratchet is a wheel rotatable mounted on the crank shaft, and in which each plate has a cam surface operable to disengage the drive pawl from the ratchet wheel.
